JP 55035876 3/1980

Primary Examiner—T. Chase Nelson*Assistant Examiner*—Ania K Dworzecka(74) *Attorney, Agent, or Firm*—John Salazar; Chad Bruggeman; Middleton Reutlinger**CLAIM**

The ornamental design for a portable heater, as shown and described.

DESCRIPTION

FIG. 1 is a perspective view of the portable heater design;

FIG. 2 is a top view thereof;

FIG. 3 is a front view thereof;

FIG. 4 is a left side view thereof;

FIG. 5 is a right side view thereof;

FIG. 6 is a rear view thereof; and,

FIG. 7 is a bottom view thereof.

The broken lines shown on the drawings are for illustrative purposes only and form no part of the claimed design.
